UNITED STATES PATENT OFFICE

1,997,146

FEED ROLLER STARTER AND BRAKE FOR
CYLINDER PRINTING TYPE PRESSES

George Mark Garfat, Hamilton, Ontario, Canada

Application September 14, 1934, Serial No. 744,051

5 Claims. (Cl. 101—344)

The object of my invention is to provide an improved feed roller starter and brake for Miehle or other cylinder printing type presses so constructed as to eliminate the common fault of unequal color distribution to the ink plate, and which permits of convenient control of the feed roller. I attain these and other objects of my invention by the mechanism illustrated in the accompanying drawings, in which—

10 Figure 1 is a side elevation of my invention applied to a cylinder printing type press;

Fig. 2 is a top plan view of same;

Fig. 3 is a side elevation of the invention detached from the printing type press, and with a portion broken away and shown in section; and

15 Fig. 4 is a front view of the invention.

Like numerals designate like parts in each of the views.

Referring to the accompanying drawings, there 20 is illustrated the main frame 1 of a Miehle type printing press, having an ink fountain 2, in which is mounted a feed roller 3. The press has a reciprocating ink-distributing table 4, over which the inking or ductor roller 5 travels. Roller 5 25 has a reduced end (or ends) 6, which is mounted on the arm 7, which in turn is operatively connected with actuating rod 13'. Member 8 is a shaft or frame member on which bracket 10 is pivotally mounted. Members 9 are rollers for spreading ink on the table 4. The bracket 10 is 30 provided with a depending arm 11, having the aperture 12', and with the forwardly extending arm 33. Aperture 12' is for the pivot 12. Bracket 10 terminates in the block 13.

35 In block 13 I provide channels 14 for the guide pins 22. The channels 14 have enlarged portions 15, in which coil springs 24 are seated. On the upper end of block 13 is mounted a suitable short strip 16, on which in turn is mounted the upper 40 end 17 of the leather strip 19, secured to the block by bolt 18. Under leather strip 19 is a metal plate 20 and members 21 which abut the outer ends of the coil springs 24 seated in chambers 15, as shown in Fig. 3. I provide nuts 23 on the 45 threaded ends of pins 22 for adjusting the distance of plate 20 and leather strip 19 from the face of block 13. Pins 22 have heads 25 engaging the steel plate 20, as shown in dotted lines in Fig. 3.

50 As shown in Figs. 3 and 4, leather strip 19 is secured by rivets 28 to the flat upper end 26 of rod 27. Rod 27 has its lower end 29 threaded for a thumb nut 30. I provide a coil spring 31 55 encircling end 29 and disposed between washers

32. Rod 27 is loosely mounted in the forward end of arm 33, as shown.

In operation, the face of leather strip 19, opposite block 13, resiliently abuts against the reduced end 6 of inking or ductor roller 5 to function as a brake, and by adjustment of thumb nut 30 the braking action may be easily and quickly adjusted. The device eliminates the common fault of unequal color distribution to the ink plate 4. By maintaining a steady pressure of the 10 brake on the end of the feed roller, the latter can be made to stop in any desired spot on the fountain roller, thereby assuring equal distribution of color to the plate 4. Steady pressure is maintained on the feed roller by the leather strip 15 19 by means of the springs 24 which press against the metal plate 20 back of the leather strip and spaced from the face of the block 13. Steel plate 20 is kept in position by the guide pins 22, the heads 25 of which engage it. By operating thumb 20 nut 30 tension on leather strip 9 may be increased or decreased, to control the roller 5 and make it stop on fountain roller 3 in as many positions as desired.

What I claim is:

1. In a device of the type described, the combination of a bracket terminating in a block, said bracket also having a forwardly extending arm disposed below the block, a strip of leather secured to the upper end of the block, a rod slidably mounted in the aforesaid arm of the bracket and to which rod the lower end of the aforesaid strip of leather is secured, means for manually adjusting the rod to increase or decrease tension on the strip of leather, a metal plate on the 30 underside of the leather strip opposite the face of the block, and means operatively engaging said metal plate to resiliently space same from the face of the block.

2. In a device of the type described, the combination of a bracket, a strip of flexible material such as leather secured to the upper end of said bracket, a rod slidably mounted in a lower portion of the bracket and to the upper end of which rod the lower end of the aforesaid strip of leather is affixed, means for manually adjusting the rod to increase or decrease tension on the aforesaid strip, a metal plate on the underside of a portion of the leather strip, and means operatively engaging said plate and pressing resiliently against same to space same from the face of the block.

3. In combination with the mechanism defined in claim 2, means for adjusting the means engag-

ing the metal plate and for retaining it in proper position relative to the bracket.

4. In combination with the mechanism defined in claim 1, means for retaining the metal plate and strip of leather in proper position on the bracket.

5. In a device of the type described, the combination of a bracket mountable on a printing press, said bracket terminating in a block, and having a spaced lower forwardly extending apertured arm, a rod slidably mounted in said arm, said rod having a threaded lower end, a thumb nut on

said end, a spring interposed between the thumb nut and the aforesaid arm of the bracket, a leather strip affixed to the rod at the lower end of the strip, and to the bracket at the upper end of the strip, a metal plate on the underside of the leather strip and spaced from the bracket, means for retaining the strip in place relative to the bracket, said means including guide pins slidably mounted in the bracket, and springs mounted in the bracket and bearing against the 10 metal plate.

GEORGE MARK GARFAT.
